America as represented by the Secretary of
War

Application February 18, 1946, Serial No. 648,524

7 Claims. (Cl. 315—39)

1

This invention relates in general to electronic oscillators and more particularly to oscillators of the cavity magnetron type.

Cavity magnetrons are a type of electronic oscillator finding most widespread use in the centimeter wavelength region. A magnetron of this type is characterized by a relatively long, straight cathode having a number of cavity resonators, all tuned to substantially the same fundamental frequency, positioned symmetrically about the cathode and at a short distance from it, and forming a portion of the anode structure thereby. These cavities have open ends which face the cathode-anode space and when a magnetic field is set up parallel to the cathode axis, and an electric field is applied perpendicular to the cathode axis, electrons which are emitted by the heated cathode will travel in spiral-like paths in the cathode-anode space. As each electron passes the vicinity of the opening in a cavity, it induces an electromagnetic field therein and, due to the coupling between individual cavities, the electromagnetic oscillations are generated in the correct phase relationships.

Since these cavities have dimensions of the order of magnitude of a wave length at the operating frequency, it will be seen that tubes operating in the centimeter wavelength region will have very small cavities. It is further apparent that a small error in the dimensioning or forming of the cavities will cause a relatively large error as percentage of a wavelength, and thus causing a relatively large error in the resonant frequency of that particular cavity. Thus cavities of these small dimensions are difficult to form with the desired accuracy.

Before the conception of the present invention, most of the cavity magnetrons of a practical nature had cavities of the shape shown in Fig. 6 of the application of Prescott D. Crout entitled "Electrical Apparatus," Serial No. 580,013, and filed February 27, 1945, now Patent No. 2,639,403. It can be seen that this design of cavity would be very difficult to manufacture with sufficient accuracy in the lower region of the centimeter wavelength range.

Accordingly, among the objects of the present invention are:

1. To provide a cavity magnetron for operation in the lower end of the centimeter wavelength region;
2. To provide such a cavity magnetron having cavity resonators of such a type that they will be comparatively easy to construct; and
3. To provide such a cavity magnetron having

15 cavity resonators which can be manufactured with a reasonable accuracy in resonant frequency.

In accordance with the present invention there is provided a cavity magnetron in which the individual cavities are rectangular in shape, as seen looking parallel to the cathode axis. At very small wave lengths, these cavities effectively become slots cut in the anode block. Since these slots may be formed with a reasonable degree of accuracy by sawing, broaching, or other means, the anode structure will be relatively simple to manufacture. Other advantages will be apparent from the specification hereinafter provided.

This invention will best be understood by reference to the drawings, in which:

Fig. 1 is a detailed drawing of a magnetron incorporating the principles of the present invention, this view being in a plane perpendicular to the cathode axis;

Fig. 2 is a detailed drawing of the magnetron of Fig. 1 in a plane parallel to the cathode axis;

Fig. 3 is a partial side view of an alternate type 25 of output coupling to that used in Fig. 1 and which may be used in connection with a magnetron incorporating the principles of this invention;

Fig. 4 is a top view of the type of coupling of Fig. 3; and

Fig. 5 shows the approximate variation of electric and magnetic fields along the radial length of a cavity.

Referring now to a description of the magnetron shown in Figs. 1 and 2, which embodies the principles of the present invention, there is shown a view looking into the end space parallel to the straight cathode in the case of Fig. 1, and a view along section A—A in the case of Fig. 2. The end space covers of this magnetron have been removed, and the source of magnetic field is not shown, for the sake of clarity. A tubular cathode 10, on the surface of at least a portion of the length of which is a coating of electron-emitting material, has a helically-shaped heater wire 11 positioned within the cathode 10. At the ends of the cathode 10 are plugs 12 and 13. Welded to the ends of the helical wire 11 are leads 14 and 15, which are welded to sleeves 16 and 17 respectively. Leads 14 and 15 may be of some substance such as tantalum. Sleeve 16 is press-fitted to the center conductor 18 of a coaxial line the outer conductor of which is 19, while sleeve 17 is press-fitted to the center conductor 20 of a coaxial line the outer conductor

3

of which is 21. Leads 18 and 20 are connected to a source of alternating current, not shown, for heater power. Hats 22 and 23, of a material such as tantalum, are held by leads 24 and 25 respectively, which are welded to the hats and to sleeves 16 and 17 respectively. These hats are positioned substantially symmetrically over the ends of the cathode.

Arranged symmetrically about the cathode 10 is an anode structure comprising ten trapezoidal-shaped copper blocks 26, 27, 28, 29, 30, 31, 32, 33, 34 and 35. Surrounding this anode structure is an annular shell 36, which is usually held at ground potential. It is therefore seen that the various copper blocks form the sides, and shell 36 forms the backs, of ten cavity resonators 37, 38, 39, 40, 41, 42, 43, 44, 45 and 46. The cross-section of each cavity, as shown in Fig. 1, is thus seen to be rectangular in shape, and of a comparatively narrow width. In practice the length of each of these cavities along a radius is made to be approximately one-quarter of a wavelength at the operating frequency of the magnetron. The shape of a cavity slot, along an axis parallel to the axis of the cathode 10, is shown in Fig. 2 to be rectangular (47), with a depth several times the width of the slot.

The outer conductors 19 and 21 which shield the leads bringing in the heater power have their ends threaded so that they may be screwed into threaded holes in shell 36, as shown on the drawings.

The radio frequency power generated by the magnetron is extracted from the end space directly above cavity 46 by coupling loop 48. This loop is welded to the end of the inner conductor 49 and to the inside of the outer conductor 50 of an output coaxial line. The outer conductor 50 is threaded, and is adapted to screw into a threaded hole in the shell 36, as shown on the drawings.

Figs. 3 and 4 show an alternative type of output coupling which may be satisfactorily used in a magnetron incorporating the principles of the present invention. Fig. 3 is a view showing a section through one of the trapezoidal-shaped copper blocks, the plane of the paper being parallel to the plane of the cathode. The face 61 of the block 60 is adjacent to the cathode-anode space of the magnetron. In the top of this block 60 is a small copper pin 62 in a push fit with the block. A copper wire 63 is soldered to this copper pin 62 and to this block 60, with silver solder being preferably used. This wire 63 may then become the center conductor of a coaxial line. It is noted that the connection between lead 63 and block 60 takes place quite near to the edge 61 of the block.

Fig. 5 shows the outline of a slot 70, the plane of the paper in this case being perpendicular to the cathode axis. Curve 71 shows the approximate variation of the magnetic field strength H of the oscillating energy in the cavity space at one particular instant of time. In this graph, distance is plotted horizontally, corresponding to the distance along the slot 70, and magnetic field strength H is plotted vertically. Curve 72 is a graph of the approximate variation of the electric field E of the oscillating energy in the cavity space at one particular instant of time. In this graph, distance along the cavity is plotted horizontally, and electric field strength E is plotted vertically.

Referring now to a description of the operation of the magnetron of Figs. 1 and 2, which incor-

porates the principles of the present invention, it is seen that the cavity resonators making up the tuned circuits of the tube are of a long, rectangular shape. Having the cavities of this shape allows the maximum amount of heat conduction away from the cathode-anode space through the anode structure, with respect to practical shapes of cavities. Theoretically, the amount of heat conduction, which is dependent to a large extent on the amount of cross-sectional area in the anode blocks, such as 26, 27, etc., in a plane normal to a diametrical plane, may be increased by forming the cavities in a trapezoidal shape, with the width of the outer extremities of the cavity being less than the width of the cavity at its inside end. However, the properties of this type of cavity would be unsatisfactory compared with the properties of the rectangular type of cavity according to the present invention. Thus the present shape of cavity allows for maximum heat conduction from the anode structure and from the cathode-anode space using practical shapes of cavities, as compared to magnetrons having the same inner and outer anode structure diameter but different shapes of cavities. A tube employing a hole-and-slot type of anode structure such as is shown in the above-mentioned application of Crout, Fig. 6, must be made with the hole diameters so large with respect to the diameter of the circle around which the holes are placed that the lateral distance between holes, as measured between the nearest points on their circumference, forms a narrow constriction, and therefore a high impedance to the conduction of heat.

35 The main advantage, however, in constructing a magnetron with cavities of the rectangular shape lies in the ease of forming the cavities. One method, for instance, of forming the anode block is to provide a cylindrical block of copper and to drill a hole of a diameter equal to the inner diameter of the anode segments 26, 27, etc. in the block. The slots may then be formed by sawing the anode block, or by broaching. Thus each slot 37, 38, etc. is formed by one machining operation.

40 45 A magnetron of the hole-and-slot type, such as is shown in Fig. 6 of the above-mentioned application of Crout must take at least two machining operations to form the cavities, and the dimensioning of the cavities is more complex. The relatively simple construction procedure of the slot type anode structure according to this invention thus makes the accurate manufacture of very short wavelength magnetrons relatively simple.

55 short wavelength magnetrons. The approximate distributions of electric and magnetic field strengths existing in the rectangular shape of cavity as used in a cavity magnetron are shown in Fig. 5. The cathode-anode space is to the left of the rectangular cavity 70. This cavity may be thought of as a short-circuit-terminated transmission line having a length approximately equal to a quarter of a wavelength at the operating frequency of the magnetron. Thus ordinary transmission line theory will explain the approximate field distributions within the cavity. 60 The magnetic field strength H starts out at the front of the cavity with a very low value. It then increases gradually until a maximum value is reached at the back of the cavity, as shown by curve 71. The electric field strength E , on the other hand, is maximum at the front of the cavity and decreases gradually until the field strength is very low in the back of the cavity, as shown by curve 72. The magnetic field strength H and the electric field strength E are substantially con- 65 70 75

stant along the depth of the cavity, i. e., along an axis parallel to the cathode axis. This of course neglects the effects of the end spaces.

As can be seen from electromagnetic field theory, the width of the cavity (its shortest dimension) determines the effective input capacitance of the cavity. Because these resonators are just small slots, the effect input capacitance is relatively high. The effective inductance of the cavity is dependent upon the length of the cavity, along a radius, and the shape of the cavity. The input inductance of a hole-and-slot type cavity is larger than the inductance of the slot type cavity, because the magnetic field strength at the back of the former type of cavity is the stronger of the two, other factors being equal. Thus the slot type cavity presents a relatively low impedance to the cathode-anode electromagnetic field, it having a relatively high effective capacitance and a relatively low effective inductance.

Another advantage of types of magnetrons according to the present invention over the hole-and-slot type is that more cavities are able to be positioned about a given diameter cathode-anode space in the former types.

Due to the narrow width dimension of this type of resonator, and because of the very short wavelengths involved, there is necessitated a type of coupling means external to the cavities themselves. Two such coupling arrangements are shown in Figs. 1 and 2 and Figs. 3 and 4.

The output coaxial line has its center conductor 49, Figs. 1 and 2, soldered to a small loop 48, which is bent around and welded to the outer conductor 50. The electromagnetic fields from each cavity are coupled into the end space just above the resonators, and the magnetic field causes current flow in coupling loop 48, thus extracting energy from this space.

Hats 22 and 23, which are kept at the same potential as the cathode, are placed directly over the cathode-anode space to repel any electrons which may stray out into the end space, back to the cathode-anode space.

In the type of coupling shown in Figs. 3 and 4, a copper wire 63 is soldered to a point on the top of one of the copper blocks 60 making up the anode structure such that the correct effective matching impedance is provided. It is desirable to make this wire 63 the central conductor of a coaxial line, so that a minimum amount of radiation may occur from this output circuit.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A cavity type magnetron comprising a cathode having a substantially straight axis, an anode structure, said anode structure comprising a plurality of substantially trapezoidal-shaped blocks positioned about said cathode, said metallic blocks forming a plurality of cavity resonators, the cross section of each of said cavity resonators in a plane normal to the axis of said cathode being substantially rectangular in shape, and means for coupling high frequency energy from said magnetron comprising a conducting wire, said wire being soldered to the top of one of said metallic blocks.

2. A cavity type magnetron comprising a cathode having a substantially straight axis, an anode structure, said anode structure comprising a plurality of trapezoidal-shaped blocks positioned about said cathode, said metallic blocks forming a plurality of cavity resonators, the cross section of each of said cavity resonators in a plane normal to the axis of the cathode being substantially rectangular in shape, and means for coupling high frequency energy from said magnetron comprising a coaxial line including an inner conductor and an outer conductor, said outer conductor adapted to be electrically connected to a source of reference potential, the end 10 of said inner conductor having the form of a loop and being electrically connected at its extremity to said outer conductor, the loop being positioned above said anode blocks.

3. A cavity type magnetron comprising a cathode having a substantially straight axis, an anode structure, said anode structure comprising a plurality of trapezoidal-shaped metallic blocks positioned about said cathode, said metallic blocks forming a plurality of cavity resonators, 15 the cross section of each of said cavity resonators in a plane normal to the axis of the cathode being substantially rectangular in shape, and means for coupling high frequency energy from said magnetron comprising a conducting means above said anode blocks.

4. A magnetron comprising a cathode, an anode, said anode comprising a plurality of metallic blocks positioned about said cathode, adjacent sides of said metallic blocks forming a plurality 20 of cavity resonators having parallel walls extending away from said cathode, and means for coupling high frequency energy from said magnetron comprising a conducting means coupled to one of said metallic blocks.

5. A magnetron as defined in claim 4, wherein the width of said slots between said parallel walls is small relative to the other dimensions of said slots.

6. A magnetron comprising a cathode having a substantially straight axis, an anode comprising a metallic block having a cylindrical hole coaxial with said cathode and a plurality of wedge-shaped slots extending radially from said cylindrical hole, the cross-section of each of said slots in a plane normal to the axis of said cylindrical hole being substantially rectangular, the width of said slots in the circumferential direction being small relative to their radial and axial dimensions, said slots constituting the resonant 45 cavities of said anode, and means for coupling high frequency energy from said magnetron comprising a conducting wire, said wire being coupled to one of said metallic blocks.

7. A cavity type magnetron comprising a cathode having a substantially straight axis, and an anode having a plurality of resonant cavities, said anode having a cylindrical hole coaxial with said cathode, each of said resonant cavities consisting of a slot extending radially from said cylindrical hole, the cross-section of each of said slots in a plane normal to the axis of said cathode being substantially rectangular, the width of said slots in the circumferential direction being small 55 relative to their radial and axial dimensions, and means for coupling high frequency energy from said magnetron comprising a coaxial line including an inner and outer conductor, said outer conductor adapted to be electrically connected to a 60 source of reference potential and said inner con-

ductor extending beyond the outer conductor into
the space immediately above the anode.
